J. L. COWEN.
HAND LETTER FOLDER.
APPLICATION FILED NOV. 7, 1919.

1,424,881.

Patented Aug. 8, 1922.

UNITED STATES PATENT OFFICE.

JOSHUA L. COWEN, OF NEW YORK, N. Y.

HAND LETTER FOLDER.

1,424,881.

Specification of Letters Patent. Patented Aug. 8, 1922.

Application filed November 7, 1919. Serial No. 336,331.

To all whom it may concern:

Be it known that JOSHUA L. COWEN, citizen of the United States, and resident of the city of New York, in the county of New York and State of New York, has invented 5 certain new and useful Improvements in Hand Letter Folders, of which the following is a specification.

This invention relates to a device for 10 folding letters, bills, circulars, and other sheets of paper of this character and is directed more particularly to a folding device adapted especially for use in connection with mailing papers of the character above-described 15 in the type of envelopes known as "window-envelopes" in which a window of transparent material is provided through which may show the address on the sheet enclosed therein.

20 In spite of the fact that window envelopes were designed primarily for the purpose of saving time and expense in rewriting or typing the address already on the enclosure, these envelopes have not enjoyed as wide a 25 use as these advantages would warrant. This is no doubt due to many difficulties which have heretofore been had with the use of such envelopes. Thus it has been found that where the enclosure is not very 30 carefully folded it may shift in the envelope until a portion or all of the address becomes hidden by the opaque portions of the envelope, or part of the writing may show through in view of the lack of accuracy 35 with which it has thus far been found possible to quickly fold the enclosure. These window envelopes have further been made with a window much larger than is really necessary, in order to provide 40 a sufficiently transparent portion in order to make sure that the full address may show through. This of course has resulted in an increased cost due to the waste of transparent material used for the window.

45 and has also made the envelope unsightly. Where care is taken in folding the enclosure so that the address will exactly register with the window, much time is necessarily consumed in the folding process, so that it has 50 for that reason been cheaper and more convenient to use the old type of envelopes.

The main object, therefore, of my invention is to provide a folding device for enclosures to be mailed in window envelopes 55 which shall free the window envelopes

from these difficulties and thus greatly increase their adoption and use.

Another object of my invention is to provide a device for folding enclosures adapted to be mailed in window envelopes so that 60 the folded enclosure will accurately fill the envelope and not shift therein.

A further object of my invention is to provide a folding device of the character described which shall so fold the enclosure 65 that only the address will show through the window of the envelope.

A still further object is to provide a folding device of the character described which shall make it possible to limit the 70 size of the window in the window envelopes to substantially the exact dimensions needed for the address to show therethrough.

Another object of my invention is to provide a folding device of the character described which shall have among others the advantages aforementioned and yet be cheap to manufacture, and efficient in its operation, and provide a quick means for accurately folding enclosures to be mailed in 80 window envelopes.

Other objects and advantages of this invention will appear from the detailed description and the features of novelty will be particularly pointed out in the claims. 85

Referring to the drawing accompanying this specification and forming a material part thereof,

Fig. 1 is a vertical elevation of one embodiment of my invention showing my 90 folding device in use;

Fig. 2 is a perspective view of the same; and

Fig. 3 is a detailed cross-sectional view 95 cut along line 3—3 of Fig. 1.

Referring in detail to the drawing, my folding device is seen to consist of a positioning member A and folding member B disposed in operative relation to each other. These members are formed preferably in one 100 piece from hard material such as sheet metal bent to provide a front plate C adapted for positioning the enclosure to be folded and a longer back plate D for folding the same when properly adjusted in position. The 105 front plate C has formed therein a recess E corresponding to the window of the window envelope. A nick F preferably in the form of an inverted V and continuous with the recess E is further cut out in the front 110

plate C to serve as a key or indicator to show where the printed matter of the letter head or other enclosure ends.

In the use of my device the letter or other enclosure F to be mailed in the window envelope is placed between the front and back plates C and D in the space enclosed by said plates and then the enclosure is shifted until the address H, only shows through the recess E in the positioning member. The nick F aids in this adjustment, serving to indicate to the user where the printed matter I ends, as will be clear from Fig. 1 in which the enclosure is shown as adjusted with the address only showing through and with a little of the last line of printed matter (shown in full lines) showing through the nick. The projecting part J of the enclosure is then turned over the edge K of the back plate D of the folding member and folded back. The folded enclosure is then removed ready to be inserted into the window envelope.

It will be understood of course that the dimensions of the plates C and D and the recess E may be made to correspond to the various standard sizes of window envelopes so that when the enclosure is folded in the device as hereinabove explained the folded sheet completely fills the envelope so that it may not shift therein, with the address only showing through the window.

In the embodiment of my invention shown and described, the device is formed from a single piece of sheet metal, but it will, of course, be understood that I do not limit myself to the particular construction shown and described inasmuch as the front and back plates C and D may be separate members secured to some intermediate supporting member and other such modifications may readily occur to one skilled in the art which will yet be within the scope of my invention and purview of my claims. The embodiment of my invention shown, however, as will be readily seen, is very simple in construction, cheap to manufacture and very easy of manipulation.

Having thus described my invention, I claim as new and desire to secure by Letters Patent:

1. A folding device for folding an enclosure for a window envelope comprising a

positioning member adapted to position the enclosure so as to bring the address thereon in positive registry with the window of the envelope when said enclosure is placed therein, said positioning member comprising a plate having a recess corresponding to the window of the envelope. 60

2. A folding device for folding an enclosure for a window envelope comprising a positioning member adapted to position the enclosure so as to bring the address thereon in positive registry with the window 65 of the envelope when said enclosure is placed therein, said positioning member comprising a plate having a recess corresponding to the window of the envelope and said folding member comprising a rear plate having a folding edge.

3. A folding device for folding an enclosure for a window envelope comprising a positioning member adapted to position the enclosure so as to bring the address 75 thereon in positive registry with the window of the envelope when said enclosure is placed therein, said positioning member comprising a plate having a recess corresponding to the window of the envelope 80 and a nick continuous with said recess.

4. A folding device for folding an enclosure for a window envelope comprising a positioning member adapted to position the enclosure so as to bring the address 85 thereon in positive registry with the window of the envelope when said enclosure is placed therein, said positioning member having a recess corresponding to the window of the envelope. 90

5. A folding device for folding an enclosure for a window envelope comprising a positioning member adapted to position the enclosure so as to bring the address thereon in positive registry with the window 95 of the envelope when said enclosure is placed therein, said positioning member comprising a plate having a recess corresponding to the window of the envelope, and another recess adjacent said first mentioned 100 recess.

Signed at New York, in the county of New York and State of New York, October, A. D. 1919.

JOSHUA L. COWEN.
